Robert Porter

United States Patent Office.

ROBERT PORTER, OF PHILADELPHIA, PENNSYLVANIA.

Letters Patent No. 74,244, dated February 11, 1868.

IMPROVED VENT FOR SHEET-METAL CANS.

The Schedule referred to in these Letters Patent and making part of the same.

TO ALL WHOM IT MAY CONCERN:

Be it known that I, ROBERT PORTER, of the city of Philadelphia, in the State of Pennsylvania, have invented a new and useful Improvement in Sheet-Metal Cans; and I do hereby declare that the following is a full, clear, and exact description of the construction and operation of the same, reference being had to the accompanying drawing, making a part of this specification, and to the letters of reference marked thereon.

The nature of my invention consists in providing a sheet-metal can with an attached adjustable vent-plug, for the purpose of facilitating in filling liquids into and discharging them from the can.

Referring to the drawings, A B is a common cylindrical tin can, having the usual short mouth-tube a', for receiving a cork or other stopper; C is the attached adjustable vent-plug. A short cylindrical tube, b', having, in this instance, a screw-thread cut around in its inner periphery, is soldered fast in the top plate of the can A B, at the side opposite to the mouth-tube a', substantially as represented in the drawings. The plug C has a screw-thread cut around in its stem c'', so as to adapt it to be screwed accurately into the short tube b'. It has also a head which produces a flat shoulder, c''', that fits down closely upon the upper end of b', when the plug is screwed down firmly thereon, or upon an intervening washer or collar, (not shown in the drawing,) so as to make an air-tight joint thereat, substantially as shown in the drawing. The lower end of the plug C has in this instance a slot, 4, cut diametrically across it to the depth of about half the length of the stem c'', and at opposite sides of this slot 4 two stays, c' c', project downward, and (after the plug C is inserted in the tube b') bent radially outward at their lower ends, so as to cause the same to come in contact with the lower end of tube b', when the plug C is unscrewed, or raised high enough to bring the upper end of its slot 4 a little above the represent the plug as raised or the vent opened.)

It will be readily seen that this simple device will afford immediate and always present and ready means of giving the necessary vent to a can, either in filling or emptying it, and that it is neither expensive of construction and application, nor liable to get out of order, nor allow the can to leak at the part when closed—points of considerable importance to dealers in paint-oils, spirits, &c.

What I claim as new, and desire to secure by Letters Patent, is—

A sheet-metal can provided with an attached vent-plug C, having stays c' c', fixed to its lower end, so as to prevent the said plug from being detached or entirely withdrawn from its cylindrical tube b', and at the same time allow of its being elevated sufficiently therein to vent the can, as occasion may require, as described and set forth.
